UNITED STATES PATENT OFFICE.

CHARLES DUCAS, OF NEW YORK, N. Y., ASSIGNOR TO CHARLES DUCAS, ALEXANDER W. WHITEFORD, AND DAVID WALTER PYE, TRUSTEES, ALL OF NEW YORK, N. Y.

TENDER TANK.

Application filed January 6, 1922. Serial No. 527,377.

To all whom it may concern:

Be it known that I, CHARLES DUCAS, a citizen of the United States, residing at New York, in the county of New York and State of New York, have invented certain new and useful Improvements in Tender Tanks, of which the following is a specification.

My invention relates to locomotive tender tanks and the like, and especially to the type 10 of tender tank in which the bottom has upstanding flanges to which superjacent parts are secured. The invention is particularly concerned with the provision and installation of dash plates in such tanks to prevent 15 injurious water-hammer effects as a result of rapid starting and stopping of the tender, etc. I aim to facilitate and cheapen the installation of the dash plates in the tank, to make the dash plates and their attachments 20 to the tank structure as strong as possible, and to avoid interference with the necessary water circulation in the tank. How these and other advantages can be attained through my invention will appear from my 25 description hereinafter of the best embodiment known to me.

The drawing shows a perspective view of a locomotive tank conveniently embodying my invention, part of the external structure 30 or "shell" being broken away and removed.

The tank here shown may be briefly described (with sufficient accuracy for my present purpose) as comprising a bottom 5 with upstanding flanges 6 at its edges; sides 35 7 overlapping and secured to said flanges; and a top 8 with downturned flanges 9 at its edges that are also overlapped by the sides 7 and secured to them. The bottom 5 is composed of three longitudinal sections 40 11, 11, and 12 having along their meeting edges upstanding flanges 15, 15 (formed by the upturned edges of the bottom plates 11, 11, and 12) by which they are secured together. As a result of this mode of construction, the bottom 5 has a couple of upstanding fore and aft internal ribs or flanges 45 15, 15, which reinforce and stiffen it. Since this mode of construction is no part of my present invention, it requires no further explanation. Nevertheless, I may here point 50 out that the plates 7, 11, 11, and 12 can all be secured to one another by horizontal rivets, and that these rivets and the bottom joints of the tank can all be effectively calked (to stop leaks arising in service).

without the necessity of lifting the heavy tank off the tender.

To obviate straining by unchecked surging of the water fore and aft, it is customary to provide tender tanks of various types with transverse dash plates. Owing to the considerable forces exerted on these dash plates by the water, they need to be very securely and substantially fastened in place. Accordingly, my present invention is especially concerned with the attachment of these dash plates.

As here shown, there are two "wing" dash plates 16, 16 corresponding in width and transverse location to the forward water legs of the tank and to the plates 11, 11 which form their bottoms. There is also a central or intermediate dash plate 18, corresponding in width and transverse location to the shorter central portion of the tank and to the plate 12. Each of the dash plates 16, 16 has a horizontal top flange 21 and a couple of vertical side flanges 22, 22, all extending laterally from the plate, and formed by bending its edges at right angles. Similarly, the dash plate 18 has horizontal and vertical laterally extending top and side flanges 23 and 24, 24. These flanges serve to reinforce and stiffen the plates 16, 16, and 18 as well as to provide for their connection 75 to the tank structure.

The dash plates 16, 16 are secured and attached to the tank top 8 by means of rivets 25 extending through said top and the abutting flanges 21, 21, and to the tank sides 7 90 by means of rivets 26 extending through said sides and the abutting flanges 22 at the outer sides of said plates. The dash plates 16, 16 are also connected and attached to the tank bottom 5 by means of gusset plates 30 secured to the bottom flanges 15, 15 by horizontal rivets 31 and to the inside dash plate flanges 22, 22 by rivets 32. Similarly, the dash plate 18 is secured and attached to the tank top 8 by means of rivets 33 taking into the flange 23, and is connected or attached to the tank bottom by means of gusset plates 35, 35 riveted to the bottom flanges 15, 15 with horizontal rivets 36 and to the flanges 24, 24 with rivets 37. The dash plate 18 is, of course, not attached to the tank sides 7, 7 at all, but only to the bottom 5 and the top 8. The lower edges of the dash plates 16, 16 and 18 are above the tops of the bottom flanges 15, 15, and 110

hence well clear of the tank bottom 5. This not only allows freest fore and aft circulation when the water is low in the tank, but also simplifies and facilitates the work of installing the dash plates.

When the bottom sections 11, 11, and 12, are riveted together, the gussets 30 and 35 are riveted to their flanges 15, 15 without any holes having been made in them for the rivets 32 or 37. After the sides 7 and the top 8 have been put on and riveted up, and the tank is ready for installation of the baffles or dash plates 16, 16 and 18, said dash plates are flanged and punched with all the rivet holes required in them. In this condition, each dash plate is taken into the tank and placed in proper position, with its top flange 21 or 23 against the tank top 8 and its side flanges 22, 22 or 24, 24 in contact with the tank side 7 and the upstanding gusset 30, or with the two upstanding gussets 35, 35. While temporarily held in position, the dash plate is used as a template for marking the required rivet holes in the tank top and sides and in the gussets. The dash plate having been removed, the holes thus marked are drilled,—after which the dash plate can be permanently riveted in position with the certainty that it will be properly placed and secured.

The superior accuracy, convenience, and economy of such a construction and mode of installation over former practice will readily be apparent to those skilled in the art. In former practice, the dash plate was secured directly to the tank bottom 5 as well as to the top 8; hence it was necessary that it should be just the right height if the result was to be a good job. Owing to the difficulties of fabricating such structures, however, it was almost impossible to predetermine the exact internal height of the tank,—to say nothing of difficulty in accurately predetermining the height of the dash plate after flanging at both top and bottom edges.

It will be observed, moreover, that the dash plates 16 and 18 greatly strengthen and stiffen the tank transversely. This stiffening is rendered the more effective by the fact that at the tank bottom 5 the dash plates 16, 18 are attached to the relatively stiff, rigid fore and aft ribs 15, 15, which distribute the stresses to the bottom without excessive concentration at any one point.

55 I claim:

1. A locomotive tender tank construction comprising a tank having top and sides, and

also a bottom plate with an upstanding flange in combination with a gusset plate secured to said flange, and a dash plate secured to said gusset plate and to the top of the tank.

2. A locomotive tender tank construction comprising a tank having top and sides, and also bottom plates with upstanding flanges secured together; in combination with a gusset plate secured to said flanges, and a dash plate reinforced and stiffened with a laterally extending side flange and secured to said gusset plate and to the top of the tank.

3. A locomotive tender tank construction comprising a tank having top and sides, and also bottom plates with upturned flanges secured together; in combination with a gusset plate secured to said flanges, and a dash plate having top and side flanges and secured thereby to said gusset plate and to the top and side of the tank.

4. A locomotive tender tank construction comprising a tank having top and sides, and also a bottom plate with an upstanding flange; in combination with a dash plate reinforced and stiffened by side and top flanges bent laterally therefrom, and connected by said flanges to said bottom flange and to the top of the tank, respectively.

5. A locomotive tender tank construction comprising a tank having top and sides, and also a bottom plate with upstanding flanges, in combination with a dash plate clear of the tank bottom at its own lower edge, laterally reinforced and stiffened by side flanges bent laterally therefrom, and attached only to the top of the tank and to its bottom flanges.

6. A locomotive tender tank construction comprising a tank with top, sides and bottom; in combination with a dash plate clear of the tank bottom at its own lower edge and attached only to the top and bottom of the tank.

7. A dash plate for locomotive tender tank reinforced and stiffened with top and side flanges for securing it, respectively, to the top of the tank and to the tank side or to means upstanding from the bottom of the tank.

8. A dash plate for a locomotive tender tank having top and side flanges with rivet holes therein, respectively, for attaching it to the tank top and to a gusset upstanding from the tank bottom.

In testimony whereof, I have hereunto signed my name.

CHARLES DUCAS,
